UNITED STATES PATENT OFFICE.

GARDNER B. GRAY, OF PITTSBURGH, PENNSYLVANIA.

SELECTIVE MEANS FOR SWITCHES.

1,209,146.

Specification of Letters Patent. Patented Dec. 19, 1916.

Original application filed April 18, 1914, Serial No. 832,722. Divided and this application filed July 25, 1914, Serial No. 853,239. Renewed May 16, 1916. Serial No. 97,980.

To all whom it may concern:

Be it known that I, GARDNER B. GRAY, a citizen of the United States, and a resident of Pittsburgh, in the county of Allegheny and State of Pennsylvania, have invented certain new and useful Improvements in Selective Means for Switches, of which the following is a specification.

The present invention relates to power actuated switches used at railroad terminals or the like, the nature of the power used being immaterial, and has for its main object selective means whereby the switch or switch points may be moved in opposite directions from a motor.

The present application is a division of application Serial No. 832,722, filed April 18, 1914, renewed as Serial No. 1713, filed Jan. 11, 1915, and renewed as Serial No. 20 42,647, filed July 29, 1915.

One feature of the invention resides in a motor rotating in one direction only together with selective means whereby the switch may be moved in opposite directions from the motor, there being means controlled by the position of the switch for determining the direction of movement imparted to the switch by the selective means.

Any suitable selective means may be utilized, but preferably, as herein disclosed, a differential transmission mechanism forms a part of the driving connections between the motor and the switch, and magnets are utilized for selectively operating the transmission mechanism.

The invention further resides in a certain relation between the selective means and an auxiliary locking device for the switch.

In the accompanying drawings the invention is embodied in a concrete and preferred form, but changes may be made within the scope of the appended claims, without departing from the legitimate and intended scope of the invention.

In the said drawings: Figure 1 is a diagrammatic view of a preferred form of a power actuated system of switch control embodying the invention. Fig. 2 is a plan view of the switch and switch machine. Fig. 3 is a longitudinal sectional view of the differential transmission mechanism. Fig. 4 is a detail view of the throw-rod and the crank for operating the same. Fig.

5 is a detail view of the lock-rod and its locking member.

Similar characters of reference indicate corresponding parts in the several views.

1 indicates the switch or switch points.

2 is the lock-rod and 3 the throw-rod, 60 both of said rods being suitably connected to said switch in a well-known manner.

4 is the motor, 5 the differential transmission mechanism, 6 the driven shaft having the crank 7 engaging in a suitable notch 65 8 in the throw-rod 3.

10 is a controller actuated by means of the cam 11 on the shaft 6 so as to move in accordance with the movement imparted to the throw-rod. 70

14 is the actuating means for the locking member 13 of the lock-rod, here shown as a double solenoid.

15 is the auxiliary locking device for the locking member of the lock-rod. 75

22 is a switch lever and 24 is a controlling means actuated by the switch lever.

25 is the source of power for operating the switch.

The switch is unlocked by moving the 80 locking member 13 out of one of the notches 600 or 601 in the lock lever 2 by means of the solenoid 14. This is accomplished by energizing the left hand end (Fig. 1) of solenoid 14 through the leads 200 in a manner 85 that need not be described. The movement to the left of the member 13 also moves the notch 102 out of the way of the lower end of the plunger 80, so that when the latter is subsequently raised the switch will 90 not be locked.

When it is desired to throw the switch, the operator moves the lever 22 to the left, thereby moving the contact 64 out of engagement with the springs 65 and 66 of the controlling 95 means 24 and placing contact 64 between the springs 67 and 68. The movement of the contact 64 into the position designated will establish a circuit as follows: From battery 25, bus bar 31, conductor 69, conductor 70, 100 spring 67, contact 64, spring 68, conductor 71, spring 72, contact 73, spring 74 of the controller 10, conductor 75, reverse magnet 76, conductor 77, to auxiliary locking device 15, and thence to common return 39 and 105 battery 25. The reverse magnet 76 forms a part of the selective means between the motor and the driven shaft 6 and when

energized tightens the band 78 on the drum 79, which thereby selectively connects the motor 4 to drive the shaft 6 in a certain direction. The energization of the auxiliary locking device 15 causes the core 80 thereof to be moved upward, thereby moving the contact 81 into engagement with the springs 84 and 85, and at the same time causing the contact 86 to bridge the space between the springs 87 and 88. Since the member 13 has previously been moved to the left, the core 80 will not engage the notch 102. This establishes a circuit as follows: from the conductor 77, to conductor 89, spring 84, contact 81, spring 85, conductor 90, motor 4, motor field 91, conductor 92, spring 88, contact 86, spring 87 and common return 39, back to battery 25. This causes current to flow through the motor 4 which by its rotation and by means of the reverse magnet 76 and the differential transmission mechanism, causes the shaft 6 to be driven in a certain direction whereby the crank 7 engaging with the notch 8 of the throw-rod 3 moves the latter and throws the switch to reverse position. The rotation of the shaft 6 causes the cam 11 to actuate the controller 10, whereby the contact 73 is moved to the right, Fig. 1, and is out of engagement with the springs 72 and 74, thereby cutting off all power between the source 25 and the controlling means 24 and reverse magnet 76 and auxiliary locking device 15, whereby 76 and 15 are both deenergized. This releases the band 78 from its clutched position and destroys the circuit through the motor. The movement of the switch further places the normal magnet 108 ready to be energized by moving the contact 99 into engagement with the springs 100 and 101 in the controller 10.

It will be observed that had current been supplied to the motor 4 before the locking dog 56 had released the lock-rod 2, the energization of the auxiliary locking device 15 would have caused the lower end of the core 80 to have engaged in the notch 102 of the locking member 13 so that, while the motor 4 would have rotated, the lock-rod 50 and the locking member therefor would both have been locked. After the switch has been moved to reverse position, the right hand end of solenoid 14 is energized through lead 201 and common return 39 in a manner that need not be described thereby locking the rod 2. And when the switch is to be moved from reverse to normal, the left hand side of solenoid 14 is again energized and the locking member 13 withdrawn.

60 When it is desired to move the switch from the reverse position to the normal position, the operator moves the switch lever 22 to the right and breaks the contact 64 between the springs 67 and 68, and causes it to bridge the springs 65 and 66, thereby establishing the

following circuit: from battery 25 to bus bar 31, conductor 69, spring 65, contact 64, spring 66, conductor 106, spring 101, contact 99, spring 100, conductor 107, to normal magnet 108, conductor 77, to auxiliary locking device 15, and thence to common return 39, back to battery 25. This energizes the said normal magnet 108, causing the band 109 to be tightened on the pulley 110, and further causes the energization of the auxiliary locking device 15 and an upward movement of the core 80. This establishes the following circuit: from conductor 77, to conductor 89, spring 84, contact 81, spring 85, conductor 90, to motor 4, motor field 91, conductor 92, spring 88, contact 86, spring 87, and common return 39. This rotates the motor 4 which by means of the differential transmission mechanism and the normal magnet 108 causes the driven shaft 6 to rotate in a direction opposite to that from which it rotated on the reverse movement, thereby causing the crank 7 to engage in the notch 8 of the throw-rod 3 and move the switch back to normal position. The movement of the shaft 6 further causes the cam 11 to move the controller 10 to the left, Fig. 1, thereby moving the contact 99 out of engagement with the springs 100 and 101 and thus cutting off power between the controlling means 24 and the normal magnet 108 and the auxiliary locking device 15, as well as the motor 4. The right hand side of solenoid 14 is now again energized and the switch locked.

Should it be attempted to move the throw-rod 3, say after sawing through or otherwise breaking the lock-rod 2, then the very act of moving the said throw-rod will cause a movement of the controller 10. If the switch were in the normal position and is moved to the reverse position, the contact 99 will bridge the springs 100 and 101 and a circuit will be established from battery 25, bus bar 31, conductor 69, spring 65, contact 64, spring 66, conductor 106, spring 101, contact 99, spring 100, conductor 107, normal magnet 108, conductor 77, auxiliary locking device 15 to common return 39, back to battery 25. This circuit would in turn, by reason of the energization of the auxiliary locking device 15, cause a circuit to be established through the motor as follows: conductor 77, conductor 89, spring 84, contact 81, spring 85, conductor 90, motor 4, motor field 91, conductor 92, spring 88, contact 86, spring 87 and common return 39. The effect of this circuit would be to cause a movement of the switch back to its normal position. Similarly if the switch is in the reverse position and it should be attempted to move it to the normal position by a physical displacement of the throw-rod 3, a circuit would be established as follows: from battery 25, to bus bar 31, conductor 69, con-

ductor 70, spring 67, contact 64, spring 68, conductor 71, spring 72, contact 73, spring 74, conductor 75, reverse magnet 76, conductor 77, auxiliary locking device 15, to 5 common return 39, back to battery 25. The energization of the auxiliary locking device 15 would, as before, establish the circuit through the motor 4 and thus cause the switch to be moved to reverse position.

10 The differential transmission mechanism 5 is preferably constructed as follows: 111 is the motor shaft disconnected from the driven shaft 6 but in alignment therewith. Mounted on the motor shaft 111 and keyed 15 thereto is a gear 393. Keyed on the driven shaft 6 is the internal gear 303. Mounted loosely on the hub of gear 303 and on the motor shaft 111 are two members 398 connected by pins 399 so as to cause them to 20 move in unison. These pins are 180° apart. Mounted loosely on the pins 399 are sleeves 397. Mounted fast on each of the sleeves 397 are three pinions 394, 395 and 396. The pinion 394 receives motion from the gear 25 393 and meshes with the internal gear 303. The pinion 395 is of slightly greater diameter than the gear 394, follows the motion of the sleeve 397 and meshes with the internal gear 308 of the pulley 79. The pinion 30 396 is of slightly less diameter than the pinion 394, follows the rotation of the sleeve 397 and meshes with the internal gear 302 of the pulley 110. The solenoids 76 and 108 are each provided with a core 112 connected 35 by means of a link 200 to two levers forming a bell crank 113, which levers are pivotally supported on the center 201 and one of which levers is longer than the other, as shown. The bands 78 and 109 pass around 40 the drums 79 and 110, and the free ends of said bands are connected to the levers 113.

If the motor shaft 111 is now rotated and the shaft 6 held against rotation, the gear 393, meshing with the pinions 394 will cause 45 them, and the sleeves 397, to rotate. Pulleys 79 and 110 being free to revolve, and the gear 303 being held against revolving movement, the pinions 394 will revolve by traveling on the internal gear 303 carrying 50 the sleeves 397 and the members 398 with them. The rotation and revolution of the sleeve 397 and pinions 395 and 396, will cause the latter to travel on the internal gears 308 and 302 and will also cause said 55 gears 308 and 302, and with them the pulleys 79 and 110, to revolve one pulley in one direction and the other pulley in the other direction, due to the difference in diameter of the pinions 394, 395 and 396. 60 If now the shaft 6 is free to rotate and the magnet 76 is energized, the core 112 thereof will be withdrawn thereby turning the levers 113 around the center 201 and tightening the band 78, so as to hold the pulley 79 65 immovable. The rotation of the sleeves 397

and pinion 395 will cause the latter to travel on the rigidly held gear 308, causing the sleeves 397, pins 399 and members 398 to revolve. The pinion 394 will attempt to travel on gear 303, but since the peripheral speed of the pinion 394 is less than that of pinion 395, said pinion 394 will drag the gear 303 with it and cause it to revolve and with it the shaft 6. The pulley 110 being movable will also revolve by the action on 70 the pinion 396 on the internal gear 302. Assume now that the shaft 6 is still free to rotate, that the magnet 76 is deenergized, the band 78 released, and the pulley 79 free to revolve. If the magnet 108 is now energized, the core 112 thereof will be withdrawn thereby turning the levers 113 around the center 201 and tightening the band 109 to hold the pulley 110 immovable. The rotation of the sleeves 397 and pinion 396 will 75 cause the latter to travel on the rigidly held gear 302, causing the sleeves 397, pins 399 and members 398 to revolve. The pinion 394 will attempt to travel on gear 303, but since the peripheral speed of the pinion 394 is greater than that of pinion 396, said pinion 394 will lag behind and will actually 80 push back the gear 303, and cause it to revolve in the opposite direction and with it the shaft 6. 85

In order to return the cores 112 to their original uppermost position, when the magnets 76 and 108 are deenergized, springs 114 are utilized.

What is claimed, is:

1. In a system of switch control, a switch, a motor rotating in one direction only, and selective means for moving the switch in opposite directions by the rotation of the motor in one direction.

2. In a system of switch control, a switch, a motor rotating in one direction only, selective means for moving the switch in opposite directions by the rotation of the motor in one direction, and controlling means for supplying power to render the motor and selective means operative.

3. In a system of switch control, a switch, a motor rotating in one direction only, selective means for moving the switch in opposite directions by the rotation of the motor in one direction, and means controlled by the position of the switch for determining the direction of movement imparted to the switch by the selective means.

4. In a system of switch control, a switch, a motor rotating in one direction only, selective means for moving the switch in opposite directions by the rotation of the motor in one direction, controlling means for supplying power to render the motor and selective means operative, and means controlled by the position of the switch for determining the direction of movement imparted to the switch by the selective means.

5. In a system of switch control, a switch, a motor rotating in one direction only, selective connections between the motor and the switch for moving the switch in opposite directions by the rotation of the motor in one direction, two magnets for rendering the selective connections operative, controlling means and circuit connections for supplying current to the motor and magnets, and means controlled by the position of the switch for selecting the magnet to be energized.

6. In a system of switch control, a switch, a motor rotating in one direction only, and driving connections including a differential transmission mechanism for moving the switch in opposite directions by the rotation of the motor in one direction.

7. In a system of switch control, a switch, a motor rotating in one direction only, driving connections including a differential transmission mechanism for moving the switch in opposite directions by the rotation of the motor in one direction, and controlling means for supplying power to render the motor and differential transmission mechanism operative.

8. In a system of switch control, a switch, a motor rotating in one direction only, driving connections including a differential transmission mechanism for moving the switch in opposite directions by the rotation of the motor in one direction, and means controlled by the position of the switch for determining the direction of movement imparted to the switch by the differential transmission mechanism.

9. In a system of switch control, a switch, a motor rotating in one direction only, driving connections including a differential transmission mechanism for moving the switch in opposite directions by the rotation of the motor in one direction, and means controlled by the position of the switch for determining the direction of movement imparted to the switch by the differential transmission mechanism.

10. In a system of switch control, a switch, a motor rotating in one direction only, driving connections including a differential transmission mechanism between the motor and the switch for moving the switch in opposite directions by the rotation of the motor in one direction, two magnets for selectively operating the differential transmission mechanism, controlling means and circuit connections for supplying current to the motor and magnets, and means controlled by the position of the switch for selecting the magnet to be energized.

11. In a system of switch control, a switch, a motor rotating in one direction only, selective connections between the motor and the switch for moving the switch in opposite directions by the rotation of the motor in

one direction, two magnets for rendering the selective connections operative, an auxiliary locking device, for the switch, and circuit connections for supplying current to the motor, controlling means and circuit connections for supplying current to the magnets and to the auxiliary locking device, and a circuit closer controlled by the position of the switch for selecting the magnet to be energized.

12. In a system of switch control, a switch, a motor rotating in one direction only, selective connections between the motor and the switch for moving the switch in opposite directions by the rotation of the motor in one direction, two magnets for rendering the selective connections operative, an auxiliary locking device, for the switch, and circuit connections for supplying current to the motor, controlling means and circuit connections for supplying current to the magnets and to the auxiliary locking device, a circuit closer controlled by the position of the switch for selecting the magnet to be energized, and a controller actuated by the movement of the switch for cutting off current from the controlling means.

13. In a system of switch control, a switch, a motor rotating in one direction only, driving connections including a differential transmission mechanism between the motor and the switch for moving the switch in opposite directions by the rotation of the motor in one direction, two magnets for selectively operating the differential transmission mechanism, an auxiliary locking device, for the switch, and circuit connections for supplying current to the motor, controlling means and circuit connections for supplying current to the magnets and to the auxiliary locking device, and a circuit closer controlled by the position of the switch for selecting the magnet to be energized.

14. In a system of switch control, a switch, a motor rotating in one direction only, driving connections including a differential transmission mechanism between the motor and the switch for moving the switch in opposite directions by the rotation of the motor in one direction, two magnets for selectively operating the differential transmission mechanism, an auxiliary locking device, for the switch, circuit connections for supplying current to the motor, controlling means and circuit connections for supplying current to the magnets and to auxiliary locking device, a circuit closer controlled by the position of the switch for selecting the magnet to be energized, and a controller actuated by the movement of the switch for cutting off current from the controlling means.

15. In a system of switch control, a switch, a motor rotating in one direction only, selective connections between the motor and

the switch for moving the switch in opposite directions by the rotation of the motor in one direction, two magnets for rendering the selective connections operative, controlling means and circuit connections for supplying current to the motor and magnets, means controlled by the position of the switch for selecting the magnet to be energized, and a controller actuated by the movement of the switch for cutting off current from the controlling means.

16. In a system of switch control, a switch, a motor rotating in one direction only, driving connections including a differential transmission mechanism between the motor and the switch for moving the switch in opposite directions by the rotation of the motor in one direction, two magnets for selectively operating the differential transmission mechanism, controlling means and circuit connections for supplying current to the motor and magnets, means controlled by the position of the switch for selecting the magnet to be energized, and a controller actuated by the movement of the switch for cutting off current from the controlling means.

17. In a system of switch control, a switch,

a motor rotating in one direction only, selective means for moving the switch in opposite directions by the rotation of the motor in one direction, and means for locking the switch when the motor is improperly supplied with power.

18. In a system of switch control, a switch, a motor rotating in one direction only, selective connections between the motor and the switch for moving the switch in opposite directions by the rotation of the motor in one direction, two magnets for rendering the selective connections operative, controlling means and circuit connections for supplying current to the motor and magnets, means controlled by the position of the switch for selecting the magnet to be energized, and means for locking the switch when the motor and magnets are improperly supplied with power.

Signed at Pittsburgh, in the county of Allegheny, and State of Pennsylvania this 21st day of July A. D. 1914.
